UNITED STATES PATENT OFFICE.

ERNEST MEYERS, OF TAUNTON, MASSACHUSETTS, ASSIGNOR TO REED & BARTON CORPORATION, OF TAUNTON, MASSACHUSETTS, A CORPORATION OF MASSACHUSETTS.

DESIGN FOR A HANDLE FOR SPOONS, FORKS, OR SIMILAR ARTICLES.

SPECIFICATION forming part of Design No. 35,861, dated April 15, 1902.

Application filed March 21, 1902. Serial No. 99,386. Term of patent 14 years.

To all whom it may concern:

Be it known that I, ERNEST MEYERS, a citizen of the United States, and a resident of Taunton, in the county of Bristol and State of Massachusetts, have invented and produced a new and original Design for a Handle for Spoons, Forks, or Similar Articles, of which the following is a specification, reference being had to the accompanying drawing, forming part hereof.

Said drawing represents a spoon or fork handle, exhibiting my new and original design.

From the narrow part of the shank of the handle, at about the point marked *a*, the design develops a number of narrow reed-like or tendril-like forms *b*, embossed upon and lying in their general direction lengthwise of the handle. These forms are shown in the drawing as somewhat overlying each other and as having curled or hooked ends, as at *c*. At or near the point of the junction of the shank and the handle proper the design develops a ribbon or streamer *d*, which lies in wavy snake-like folds or coils and extends partly or quite across the handle. All the

said forms which enter into the composition conform to the general shape of the article to which they are to be applied. Around the edge of the broad part of the handle the design develops the fillets *e* and *e'*, which are surmounted by the scroll figure *f*. At the lower end of the shank, below the point marked *a*, where the shank widens out at its junction with the bowl of the spoon or fork, the design develops the forms of ribbons or streamers, lying in S-like folds or coils intertwined one with another and conforming in general outline to the shape of the article to which they are applied. These intertwined and coiled streamers are shown in the drawing at *g*.

What I claim, and desire to secure by Letters Patent, is—

The design for a handle for spoons, forks or similar articles, substantially as shown and described.

Signed by me at Taunton this 18th day of March, 1902.

ERNEST MEYERS.
